UNITED STATES PATENT OFFICE

157,558

COLLAPSIBLE BACKREST FRAME

Sonia Anderson, Los Angeles, Calif.

Application February 16, 1948, Serial No. 144,520

Term of patent 14 years

(Cl. D15—8)

To all whom it may concern:

Be it known that I, Sonia Anderson, a citizen of the United States, residing at Los Angeles, in the county of Los Angeles and State of California, have invented a new, original, and ornamental Design for a Collapsible Backrest Frame, of which the following is a specification; reference being had to the accompanying drawing, forming part thereof.

Fig. 1 is a perspective view of a collapsible backrest frame, showing my new design.

Fig. 2 is a front elevational view thereof.

Fig. 3 is a top plan view thereof.

Fig. 4 is a side elevational view thereof.

Fig. 5 is a perspective view thereof, showing the arms in folded or collapsed condition.

I claim:

The ornamental design for a collapsible backrest frame, substantially as shown.

SONIA ANDERSON.
